UNITED STATES PATENT OFFICE.

THOMAS PROSSER, OF MONTREAL, QUEBEC, CANADA, ASSIGNOR OF ONE-HALF TO JOHN DUMARESQ, OF SAME PLACE.

APPARATUS FOR OPERATING SELF-FLUSHING CLOSETS.

SPECIFICATION forming part of Letters Patent No. 279,183, dated June 12, 1883.

Application filed October 21, 1882. (No model.)

To all whom it may concern:

Be it known that I, THOMAS PROSSER, of the city of Montreal, in the district of Montreal and Province of Quebec, Canada, have invented certain new and useful Improvements in Apparatus for Operating Self-Flushing Closets; and I do hereby declare that the following is a full, clear, and exact description of the same.

10 My invention is specially intended for use in hotels, railway-stations, and other places where closets are in public use, as not only is the working automatic and certain, but the apparatus cannot be tampered with, and no waste of water can occur.

15 The principal feature of the invention is that the cistern or vessel for holding water in the apparatus is normally dry—that is, always empty except during the time that the closet-seat is occupied.

20 The construction may be thus briefly described: The cistern has arranged inside it a Lambert valve and ball-cock, regulating the inflow from the main. The outlet, which is closed by a washer, communicates directly with the basin of the closet. A lever pivoted in bearings 25 formed on the lid of the cistern, and operated by a rod attached to the seat, has pivoted to its other end a link, to the end of which is secured the washer or stopper of the outlet, this link being slotted to receive the rod of the ball-cock, whereby the inlet is held closed when the stopper is lifted, and opened when the outlet is closed.

30 For full comprehension of the invention reference must be had to the annexed drawings, in which—

35 Figure 1 is a longitudinal sectional elevation of the apparatus with the parts in their usual position; and Fig. 2, the same, but showing the position of the parts at the instant when, by pressure on the seat, the outlet is closed and inlet opened and the cistern begins to fill.

40 Similar letters of reference indicate like parts.

45 A is the cistern, made of cast-iron, galvanized iron, wood lined with lead or zinc, &c., or any usual or suitable material, and preferably 50 of such size as to contain up to the line of flo-

tation of the ball the quantity sufficient to flush the basin—say about two gallons. The cistern is covered with a lid, A'.

B is the inlet-pipe to the cistern, connected with the main, and B' the outlet-pipe, taken 55 from the cistern to the arm of the basin, which is preferably a hopper-basin and trap.

C is a Lambert ball-valve, c being the rod, and C' the ball stopping and regulating the admission of water to the cistern. This ball 60 C' is raised and lowered, irrespective of its flotation, by means of a slotted link, D, through which the rod c passes, this link being pivoted to the end of the lever E, fulcrumed in suitable bearings, e, formed on the lid A'. 65

On the lower end of the link D is carried the washer or stopper F, which may be made either as shown or of any form found suitable for closing the outlet B'.

70 The outer end of the lever E is connected by means of a rod or link, G, with the seat H, resting on gudgeons h in proper bearings, the relative position of E and H being adjusted by jam-nuts g, working on the screwed end of rod G. 75

75 On the front end of the lever E is secured a weight, E', sufficient to counterbalance the weight of the ball C' and stopper F, keeping the inlet B closed and the outlet B' open, this being the normal position of the apparatus. 80

85 The operation of the invention is as follows: When pressure is brought to bear upon the seat sufficient to overcome the resistance of the weight E', the front end of the lever E is raised by the rod G, the rear end being correspondingly depressed, thus allowing the ball C' to fall, thereby opening the inlet-pipe B, and simultaneously closing, by means of the washer F, the outlet-pipe B'. The water then flows into the cistern until the ball C' is raised therewith to such a height as to close the inlet-valve C. The charge of water then remains in the cistern until the pressure on the seat is removed, when the parts resume their normal position, the inlet being still kept closed and the outlet opened, so as to allow of the rush of the full charge of water into the basin and to completely empty the cistern. 90

95 It may be remarked that by my invention the chance of injury to the cistern from the 100

freezing of its contents is entirely done away with.

What I claim is as follows:

1. In an apparatus for operating self-flushing closets, the combination of a cistern or reservoir, normally dry, with inlet and outlet valves controlled by a pivoted weighted lever fulerumed in bearings above the water-level of the cistern, and connected by a rod with the rear of the seat, the whole operated automatically by pressure on such seat, all as herein set forth, and for the purposes described.
2. The combination, with the normally-dry cistern A, of a pivoted weighted lever con-

nected by a rod with the rear of the seat and 15
operated by pressure thereon, and a slotted
link pivoted to the lever and carrying a stop-
per for the outlet, and serving to raise a ball-
cock for regulating the supply, whereby the
inlet is held closed when the stopper is lifted, 20
and the inlet shall be opened when the outlet
is closed, and the exact quantity of water to be
discharged automatically gaged, all as herein
set forth.

THOMAS PROSSER.
